US00D849749S

(12) **United States Design Patent** (10) **Patent No.:** **US D849,749 S**
(45) **Date of Patent:** **** May 28, 2019**

(54) **CROWN FOR ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Brad G. Boozer**, Cupertino, CA (US); **Daniel J. Coster**, San Francisco, CA (US); **Daniele De Iuliis**, San Francisco, CA (US); **Colin Ely**, Cupertino, CA (US); **M. Evans Hankey**, San Francisco, CA (US); **Phillip M. Hobson**, Menlo Park, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Fletcher Rothkopf**, Los Altos, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Michael Benjamin Wittenberg**, Sunnyvale, CA (US); **Rico Zörkendorfer**, San Francisco, CA (US)

(73) Assignee: **Apple Inc.**, Cupertino, CA (US)

(**) Term: **15 Years**

(21) Appl. No.: **29/640,617**

(22) Filed: **Mar. 15, 2018**

Related U.S. Application Data

(63) Continuation of application No. 29/593,685, filed on Feb. 10, 2017, now Pat. No. Des. 813,239, which is

a continuation of application No. 29/499,071, filed on Aug. 11, 2014, now Pat. No. Des. 778,912.
